UNITED STATES PATENT OFFICE.

HERBERT J. BUCHSBAUM, OF CHICAGO, ILLINOIS.

BELT-BUCKLE.

1,375,774.

Specification of Letters Patent. Patented Apr. 26, 1921.

Application filed May 8, 1920. Serial No. 379,822.

To all whom it may concern:

Be it known that I, HERBERT J. BUCHSBAUM, a citizen of the United States, residing at Chicago, in the county of Cook and State of Illinois, have invented a certain new and useful Improvement in Belt-Buckles, of which the following is a full, clear, concise, and exact description, reference being had to the accompanying drawings, forming a part of this specification.

My invention relates to belt buckles and has for its purpose the provision of an extremely simple device of this character, which shall have an extremely small number of parts so arranged however that suitable means hold one extremity of the belt permanently in the buckle and other means suitably clamp the free belt tongue in any given desirable position without the aid of the customary holes in such belt tongue.

My invention further contemplates the provision of a structure which when closed is box like in its nature.

I will describe several forms which my invention may take more in detail by referring to the accompanying drawings in which—

Figure 1 is a front view of the belt buckle;

Fig. 2 is a rear view of the same in its closed condition;

Fig. 3 is a side view thereof;

Fig. 4 is a longitudinal sectional view thereof;

Fig. 5 is an end view;

Fig. 6 is a fragmentary longitudinal section of a modified form of buckle;

Fig. 7 is a rear view of a further modified form, and

Fig. 8 is a longitudinal section of a further modification.

Referring to Figs. 1 to 5 it will be apparent that but three distinct elements are needed for the construction of the entire buckle and these means furnish the clamp

elements for the two extremities of the belt. These three elements are respectively the front plate 10, the rear cover plate 11 and the clamp element 12. All three are pivotally connected together, and in the particular embodiment here shown swing about the same axis. The front plate consists of the front wall 13 and the two rearwardly extending side walls 14, 14. This front plate has holes 15 which support extending pins or trunnions 16. These trunnions form part of the element 12. There is thus a pivotal

connection between the elements 10 and 12. The trunnions 16 also pivotally support the rear cover plate 11, by virtue of extending ears, which project longitudinally of the element 11. A box like structure is formed between the elements 11 and 10 as is readily apparent. The elements 10 and 11 may be locked together by reason of the projections 18 which protrude from the side walls 14 of the front plate 10. These projections enter into recesses 19 provided in the side walls of the element 11. The material of which the structure is made is somewhat spring like and the projections 18 for this reason are enabled to snap into the recesses 19 to hold the parts in their closed position. When the device is used in connection with a belt the element 11 is swung open clockwise, (Fig. 4) and the clamping element 12 is also swung into the same direction. The belt extremity 20 is then brought into the right hand end of the front plate 10 and the clamp element 12 is swung back into the position it is shown as occupying in Fig. 4, thus holding this belt extremity 20 permanently in place. The belt may then be adjusted about the body of the wearer and the free belt tongue has to be inserted into the opposite end of the front plate 10 so that it passes outwardly over the clamp element 12 through the opposite end of said front plate 10. The rear cover plate 11 is then swung into the position occupied in Fig. 4 clamping this free belt tongue 21 between its inner edge 22 and the upper surface of the clamping element 12. The free belt tongue 21 may thus be locked in any desired position without the provision of eyelets or holes customarily employed in such free belt extremities. The forward extremity of the clamping element 12 has a cut away portion 23 so that suitable engagement may be had therewith in order to release it from its gripping position upon the belt tongue.

In Fig. 6 I show a modified form of the invention in which clamping element 12^a has a projection 24 which may coöperate with an indentation 25 provided in a modified rear cover plate 11^a. The belt may then be clamped between the elements 24 and 25 without projecting through the entire buckle if so desired.

In Fig. 7 a further modification is shown, in which the rear plate 11^b is provided with slots 26 at the belt gripping end thereof to increase the resiliency of this portion of the

rear plate. In this form the rear plate is also provided with a plurality of indentations 27 to form gripping projections on the inner surface thereof, so as to cause a firmer gripping of the belt end 21.

In Fig. 8 a still further modification is shown in which the rear plate 11^c is provided with a transverse slot 28 of sufficient width to receive the belt end 21 readily therethrough. The kinking of the belt at 29 in this form, when the rear plate is closed, together with the clamping action of the rear plate, holds the belt end 21 from movement relatively to the buckle.

From what has thus been shown and described my invention will be readily apparent to those skilled in the art.

Having thus described the several forms of the invention what I claim as new and desire to secure by Letters Patent is:

1. A device of the character described comprising a front plate, a clamping element swingingly associated with said front plate and having means for securing a belt extremity in position in said front plate, and a second clamping element mounted upon said front plate and adapted when in clamping position to clamp the free belt extremity between said second clamping element and said first clamping element.

2. A device of the character described comprising a front plate, a clamping element swingingly mounted on said front plate and having means for securing a belt extremity in position in said front plate, and a second clamping element swingingly mounted upon said front plate and adapted when in clamping position to clamp the free belt extremity between said second clamping element and said first clamping element.

3. A device of the character described comprising a front plate, a clamping element swingingly associated with said front plate and having means for securing a belt extremity in position in said front plate, and a second clamping element swingingly mounted upon said front plate and adapted when in clamping position to clamp the free belt extremity between said second clamping element and said first clamping element, said two clamping elements swinging about the same axis.

4. A device of the character described comprising three elements pivotally united by a common pivot, means whereby one of said elements is adapted to clamp a belt extremity between it and the second element, and means whereby the third element is adapted to clamp a free belt extremity between it and the first aforesaid element.

5. A device of the character described comprising a front plate, a clamping element swingingly associated with said front plate and having means for securing a belt

extremity in position in said front plate, a second clamping element mounted upon said front plate and adapted when in clamping position to clamp the free belt extremity between said second clamping element and said first clamping element, said first aforesaid clamping element having a projection and said second aforesaid clamping element having a recess, said projection and recess co-operating to clamp said free belt extremity.

6. A device of the character described comprising a front plate, a clamping element swingingly associated with said front plate and having means for securing a belt extremity in position in said front plate, and a second clamping element mounted upon said front plate and adapted when in clamping position to clamp the free belt extremity between said second clamping element and said first clamping element, said first aforesaid clamping element having a cutaway portion whereby it may be actuated into or out of clamping position.

7. A device of the character described comprising a front plate, a clamping element swingingly mounted on said front plate and having means for securing a belt extremity in position in said front plate, and a second clamping element mounted upon said front plate and adapted when in clamping position to clamp the free belt extremity between said second clamping element and said first clamping element, said second clamping element being provided with an indentation adapted to engage said free belt extremity to firmly grip the same.

8. A device of the character described comprising a front plate, a clamping element swingingly associated with said front plate and having means for securing a belt extremity in position in said front plate, and a second clamping element mounted upon said front plate and adapted when in clamping position to clamp the free belt extremity between said second clamping element and said first clamping element, said second clamping element being provided with slots to increase the resiliency thereof.

9. A device of the character described comprising a front plate, a clamping element swingingly associated with said front plate and having means for securing a belt extremity in position in said front plate, and a second clamping element mounted upon said front plate and adapted when in clamping position to clamp the free belt extremity between said second clamping element and said first clamping element, said second clamping element being provided with an indentation adapted to engage said free belt extremity to firmly grip the same and with slots to increase the resiliency thereof.

10. A device of the character described

comprising a front plate, a clamping element swingingly associated with said front plate and having means for securing a belt extremity in position in said front plate, 5 and a second clamping element mounted upon said front plate and adapted when in clamping position to clamp the free belt ex- tremity between said second clamping ele- 10 ment and said first clamping element, both said clamping elements being mounted on said front plate.

In witness whereof I hereunto subscribe my name this 24th day of April, A. D., 1920.

HERBERT J. BUCHSBAUM.
